ATTORNEY.

UNITED STATES PATENT OFFICE

ROBERT R. JONES, OF AKRON, OHIO, ASSIGNOR TO THE FIRESTONE TIRE AND RUBBER COMPANY, OF AKRON, OHIO, A CORPORATION OF OHIO

APPARATUS FOR MANUFACTURING RUBBER AND RUBBERIZED FABRIC STOCK

Application filed August 19, 1926. Serial No. 130,188.

This invention relates to methods and apparatus for calendering or forming rubber or rubberized fabric stock.

Heretofore, this stock has been cooled as it issues from the calenders or other rubber forming machines either by passing through a tank of cooling liquid or by passing over rollers chilled with a refrigerant. These devices are not entirely satisfactory because of the amount of space required by the former and the expense in installation and maintenance of the latter.

The present invention has for its object the provision of simple procedure and inexpensive apparatus adapted effectively to cool rubber or rubberized stock issuing from rubber forming machines such as calenders.

Specifically, the invention is directed to the provision of a cooling mist or spray formed by a moisture-laden air blast directed against it, whereby the cooling is effected mainly by evaporation of the moisture from the surface of the stock rather than by conduction.

The foregoing and other objects are obtained by the procedure and the apparatus for carrying out the same which are described below and illustrated in the accompanying drawings.

Of the accompanying drawings:

Figure 1 is a diagrammatic side elevation of apparatus embodying the invention;

Figure 2 is a plan of one of the cooling devices used therein;

Figure 3 is a section on line 3—3 of Figure 2;

Figure 4 is a plan of another apparatus embodying the invention; and

Figure 5 is a detail side elevation of one of the cooling devices used therein.

Referring to Figures 1 to 3 of the drawings, 10 indicates a calendar such as used for rubberizing fabric. The stock 11 passes through calendar 10 from a reeling device 12 and is drawn from the calendar over a

vertical series of offset rollers 13, 14, 15 and 16 by means of a winding and reeling device 17.

Cooling of the stock 11 is accomplished by the directing of a moisture laden air blast 50 against the opposite sides thereof. This is effected by a cooling device indicated generally at 18, and directing its blast against roller 13 and by a second similar cooling device 19 directing its blast against roller 14. 55

Devices 18 and 19 each include a suitably supported upper pipe 19 having apertures through which water can flow and a lower pipe 20 having apertures through which blasts of air may be directed into the stream 60 of water from pipe 19 and toward the roller over which the stock 12 is traveling. Beneath pipe 20 there is preferably arranged a blast-directing vane 21 extending in a direction toward the roller on which the stock is 65 to be cooled. Suitable valves, indicated at 22 and 23, may be employed to control the respective supplies of water and air.

In the form of the invention shown in Figures 4 and 5, arrangement has been made 70 for cooling strip rubber stock 24, 24 issuing from a forming machine and being conducted therefrom on a belt 25. Cooling devices embodying the invention are arranged at 26, 26 on opposite sides of the belt. Each of the 75 devices include an upper water pipe 27, delivering a stream therefrom at 28, and two lower converging air pipes 29, 29 directing blasts of air into the stream at angles from opposite sides thereof, the ends of the three 80 pipes preferably being enclosed by a spray directing nozzle piece 30. Control of the water supply may be effected by a valve 31 and of the air supply by a valve 32.

In the use of either form of the invention, 85 the blasts of moisture-laden air are directed against stock, the air serving to convey the water to the stock and to rapidly evaporate the water at the surface of the stock. The water continues to evaporate from the stock 90

as it passes to the reeling device so that the cooling proceeds from the spray devices to the reeling device over a considerable distance without necessitating the use of long tanks and refrigerated rollers.

Modifications of the invention may be resorted to without departing from the spirit thereof or the scope of the appended claim.

What is claimed is:

- 10 The combination with a rubber forming machine of means for directing a spray or mist of water against each surface of the stock issuing therefrom.

ROBERT R. JONES.
